UNITED STATES PATENT OFFICE.

HAROLD WEDDLE, OF NEW YORK, N. Y.

DESIGN FOR A TEA-BOX.

46,763.

Specification for Design.

Patented Dec. 8, 1914.

Application filed May 18, 1914. Serial No. 839,461. Term of patent 14 years.

To all whom it may concern:

Be it known that I, HAROLD WEDDLE, a subject of the King of England, residing at New York city, in the county of New York and State of New York, United States of America, have invented a new, original, and ornamental Design for Tea-Boxes, of which the following is a specification, reference being had to the accompanying drawing, forming part thereof.

Figure 1 of the drawing is a plan view of the top of a tea box showing my new design, Fig. 2 is a side elevation of my improved box, and Fig. 3 is a plan view of the end thereof.

I claim:

The ornamental design for a tea box, as shown.

HAROLD WEDDLE.

Witnesses:

GEORGE H. PEAL,

H. R. CULBERTSON.
